UNITED STATES PATENT OFFICE.

FRED A. COOK, OF LONGVIEW, ILLINOIS.

CONCRETE HOUSE AND CAVE BUILDING FORM.

1,215,318.

Specification of Letters Patent.

Patented Feb. 6, 1917.

Application filed May 5, 1916. Serial No. 95,677.

To all whom it may concern:

Be it known that I, FRED A. COOK, a citizen of the United States, residing at Longview, in the county of Champaign and State 5 of Illinois, have invented certain new and useful Improvements in Concrete House and Cave Building Forms, of which the following is a specification.

My invention relates to building forms 10 for the erection of concrete houses such as garages, poultry, dairy and hog house and caves and other small buildings. The object of my invention is to provide a cheap and simple yet rigid construction which can be 15 easily assembled and removed at a minimum cost. The all steel forms on the market are beyond the means of the small contractor in the small towns where most of his work is on the farm and would not justify him in a 20 more expensive equipment.

I attain these objects by the forms illustrated in the accompanying drawings in which—

Figure 1 is a perspective view looking 25 down on and into said forms with concrete partly filled up on one side, Fig. 2 is a broken section of a retaining wall form used in the cave form which extra wall may be set at any distance from the main wall in 30 order to retain enough dirt to keep the interior of the cave at an even temperature; Fig. 3 is a wall form similar to Fig. 2 and used as the main wall for buildings hereto described; Fig. 4 is a detailed view of arch 35 rafter support for the roof so constructed as to make the same collapsible and easily removed after the concrete roof has set, Fig. 5 shows the method of construction of the inner and outer walls and taking out bolts 40 of the inner wall forms and removing the channel iron studding which helps to form a tie from the studding to the inner wall making the wall forms collapsible so that they may be used repeatedly. Fig. 6 is a cornice 45 form or mold which can be used when a cornice is desired or omitted in the cave form or concrete building. Fig. 7 is an enlarged drawing showing the bracket for the cornice form Fig. 6. Fig. 8 is a detailed view of 50 the wall tie. To make this wall tie self-adjustable an angle or channel iron studding should be used.

Similar letters refer to similar parts throughout the several views.

55 The inner plank 7, is held in position by the cross ties 5 and the supporting rafters 2

which in turn support the rafter arch 25 in which are embedded the angle irons 3 which support a sheeting on which is placed a stiff metal covering 8. The outer plank wall 14 is held in place by the wall ties 22 and the cornice brackets 12. The cornice forms 8 and 9 and the exterior wall forms 15 are held in place by wall ties 22 and the wall spacers 19 constitute the frame work of the forms on which I base my invention.

The outer plank wall 14 is held in position by being attached to the uprights 17 which are angle iron studdings and at the inner corner of the inner form uprights 1, 70 which are channel iron studdings are attached by the device shown in 16, Fig. 5 being a thin strap of iron attached permanently to the plank form with a threaded hole in the center of said strap penetrating 75 a raised collar attached thereto, said metal strap being sunk into the plank in order to leave a smooth surface thereon and attached to the plank form then held to the corner studding support which is shaped as 80 a channel iron 1 by a screw headed bolt 24 penetrating the raised collar 16, Fig. 5 which bolt can be easily removed from the inside thereby releasing the inner wall form. The outer and inner wall forms are held 85 together by an iron tapering circular wall tie 22 one end being threaded and the diameter increasing toward the head of the bolt so that it can be easier removed than the ordinary tie bolt. The wall tie is ad- 90 justed to place by crank nut 11 and held in position by the channel or angle iron studding 17 and 1. These iron studdings are so punched that the square head of the wall tie 28 is held firmly by the outwardly pro- 95 jecting flange of the angle or channel iron and the tapered bolt being the desired length for the desired width of the concrete wall and on the screw end the shoulder of the crank nut is of such length that the arm 100 interferes with the outwardly projecting flange of the channel or angle iron studding whenever the supporting wall form 29 and 14 has reached its exact position on the wall tie. In event the wall form 29 or 14 bulges in, the concrete will force it back up against the crank nut in position, the inner wall first being braced and set firmly in line by cross ties 5, thus making the wall tie self- 105 spacing.

The supporting rafters 2 are composed of channel irons with flanges upwardly in

which rest the arch timbers 25. In these timbers are embedded the angle irons 3 which form a support for the sheet iron covering 8. These arch supports are held 5 in place by curb headed pins 23 placed in upper end on 1 Fig. 4 which may be easily removed when the concrete roof has set. The rafter supports may be braced by the supports 6 and 4. 8 is also a base for cornice forms of sheet iron and bent upwardly which is shown by 9 to form a fascia, and an angle iron 30 is riveted to the upper edge thereof where running level. Where arched a curved circular rod 31 is used to aid stiffness at the upper circular edge of 9, said sheet iron 8 being bent around said rod. The cornice forms are held in place by brackets 12 attached to the wall forms by devices 16 heretofore described making the 20 wall bracket possible to be detached from the main wall form after concrete is set. The extra or retaining wall forms 15 and 29 are similar in construction to the main walls and are held in position by the wall ties 22 25 and attached to the main walls by the wall spacer 19 which is a strap of iron of any designed length with a hook at one end attached to the outer wall form by a collar rivet bolt 20 and the inner wall form by a 30 collar rivet bolt.

I am aware that prior to my invention forms for making concrete buildings have been in use and I do not claim such a combination broadly: but I claim,

35 1. The combination, in concrete house and cave form construction having angle and channel iron studding to hold the form walls in upright position, channel iron rafters, arch-shape timbers held thereby, 40 angle irons extending transversely of and embedded in said timbers, a sheet iron cover thereover to form a roof, angle pins fastening the rafter ends to said studding, angle iron ties connected to opposed rafters 45 intermediate of their length and angle pins connecting said two last named elements.

2. The combination in concrete house and

cave forms, of outer walls consisting of angle iron studding and forms fastened thereto, an inner wall and an adjustable 50 self-spacing wall tie connecting said walls, said tie consisting of a tapering square-headed bolt threaded at one end and a crank nut, the shoulder and arm of such crank nut being of such length as to permit the wall 55 form to be spaced and adjusted to the exact required position for the width of the concrete wall, all in combination with a structural iron extending along said outer wall and having a flange which forms an abutment for said crank nut, substantially as specified.

3. In a concrete form, channel iron uprights, forms, and means for connecting said forms to said uprights, consisting of a 65 narrow strap of metal with holes at each end thereof, a raised tapering boss in the center thereof, and a threaded hole in such boss, said strap being embedded in the form flush with the inner side thereof, and a screw-headed bolt passing through the channel iron and engaging said tapered boss to tie said forms to said channel iron, substantially as specified.

4. In concrete house and cave form, a 75 cornice form comprising a stiff sheet iron extending outwardly and upwardly from the outer wall of the main form, an angle iron fastened to the upper edge of the cornice form where it runs horizontal, a round rod 80 fastened to the upper edge where it is arch-shaped, brackets supporting the same, headed bolts passing through the brackets and bolt anchors, each consisting of a narrow strap of metal with a raised tapering 85 threaded boss, said anchors being embedded in and fastened to the wall form, substantially as specified.

In testimony whereof I hereunto affix my signature in the presence of two witnesses. 90

FRED A. COOK.
